UNITED STATES PATENT OFFICE.

GEORGE JAMES HONE, OF LONDON, ENGLAND.

GRAB FOR EXCAVATING AND ELEVATING CLAY, COAL, &c.

SPECIFICATION forming part of Letters Patent No. 546,885, dated September 24, 1895.

Application filed November 21, 1894. Serial No. 529,502. (No model.)

To all whom it may concern:

Be it known that I, GEORGE JAMES HONE, mast-maker, a subject of the Queen of Great Britain and Ireland, residing at East Ham, 5 London, in the county of Essex, England, have invented certain Improvements in Grabs for Excavating and Elevating Clay, Coal, Coke, or other Material, of which the following is a specification.

10 This invention relates to improvements in the construction of excavators or grabs which are provided with an arrangement of sheaves mounted in sliding and fixed parts of the excavator-frame whereby a more powerful purchase is obtained on the material to be excavated, and the apparatus operates more efficiently than hitherto, and my invention further relates to details in the construction of such grabs or excavators.

15 20 According to this invention, one set of sheaves is mounted in a cross-head sliding in guides, the block for the second set of sheaves being secured to the base of the said guides.

In order that the invention may be clearly 25 understood I will describe it with reference to the accompanying drawings, which illustrate a convenient way of carrying out this invention, in which—

Figure 1 shows the apparatus in side elevation with the blades or buckets open. Fig. 30 2 shows the apparatus closed, and Figs. 3 and 4 are plan views of the sheave-blocks, Fig. 3 showing the sheave-block on the sliding cross-head and Fig. 4 the sheave-block fixed at the 35 lower part of the apparatus. Fig. 5 shows in section drawn to a larger scale a spring-buffer to which the end of the hauling-chain is attached for deadening the shock given by a sudden pull or jerk on the hauling-chain to 40 that part of the apparatus to which the spring-buffer is attached.

A represents blades or buckets pivoted at a to the lower end of a guide-frame C.

D represents tie-rods hinged at their lower 45 ends d to the outer ends of the blades or buckets A and at their upper ends to the cross-head E, sliding in the guide-frame C, which cross-head is provided with sheaves e e². To the lower end of the guide-frame C is secured 50 a pulley or purchase block F, containing

sheaves f f² f³, the relative position of the sheaves in the cross-head E and in the block F being shown in plan views, Figs. 3 and 4.

G is balanced chain attached to the cross-head at g for retaining the said cross-head in 55 position.

H is the main hauling-chain passing from the crane through the central hole e³ in the cross-head E down through the hole f⁴ in the block F and round the central sheave f on the 60 said block F. The chain then passes up over the sheave e on the cross-head E, returning down round the sheave f² on the block F and up again round the sheave e² on the cross-head E, then down round the sheave f³ on the 65 block F, and, finally, up to the cross-head E, to the lower side of which it is attached through a spring-buffer K, Fig. 5. The spring-buffer K is formed by elastic blocks k' with interposing washers k², up through which 70 passes the connecting-link k³, having a screw-nut on the end of the link bearing on topmost washer, all being inclosed in a cylindrical case k⁵ with a metal cap k⁶. I have described this buffer as suitable for the apparatus, but 75 other known forms of spring-buffers may equally well be used.

When it is desired to close the blades or buckets A for the purpose of excavating and removing the material, the said buckets being in an open position (shown in Fig. 1) and resting on the said material, the main chain H is hauled in, depressing the cross-head E and causing the tie-rods D to be thrust down, so that the blades or buckets A excavate the material and meet together in a closed position beneath the said material, as in Fig. 2. The apparatus may then be raised by continued hauling of the main chain H, and may be 85 swung round to the desired position for discharging the load, which is effected in the ordinary manner by keeping the balance-chain 90 taut and allowing the main chain to run out. The apparatus will then reassume the position shown in Fig. 1, and is ready for lowering again onto the material to obtain a fresh 95 load.

By the arrangement of sheaves and pulley-blocks on the sliding and fixed parts, as hereinbefore described, an increase of purchase 100

is gained, which may be varied by using a greater or less number of sheaves in the pulley-block and cross-head, according to the consistency of the material to be operated on 5 and the greater or less purchase required to be exerted on the material to be removed.

I claim as my invention—

1. In excavators or grabs, the combination of a guide frame provided with a block F carrying sheaves f, f^2, f^3 , and having a central hole f^4 , with a cross-head E sliding in the guide frame and provided with sheaves e , and e^2 , and having a hole e^3 , rods connecting the blades with the cross-head, and a hauling

chain, all substantially as and for the purposes set forth.

2. In excavators or grabs, the combination with the sheaves on the block F of the sheaves on the crosshead E and a spring buffer attached to the said crosshead, substantially as 20 and for the purposes hereinbefore described.

In testimony whereof I have signed my name to this specification in the presence of two subscribing witnesses.

GEORGE JAMES HONE.
